UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

BINDER DEVICE.

1,317,249.

Specification of Letters Patent. Patented Sept. 30, 1919.

Application filed November 29, 1918. Serial No. 264,730.

To all whom it may concern:

Be it known that I, GEORGE P. WIGGINTON, a citizen of the United States, residing at the city and county of Kalamazoo, State 5 of Michigan, have invented certain new and useful Improvements in Binder Devices, of which the following is a specification.

This invention relates to improvements in binder devices.

10 The main objects of this invention are:

First, to provide an improved binder device which facilitates the use of temporary binders or loose sheet holders and loose sheets for accounting purposes.

15 Second, to provide an improved device which is capable of being quickly adjusted to permit the operator to view both sides of a sheet and also to facilitate the manipulation of the sheets having accounts on both 20 sides.

Further objects, and objects relating to structural details, will definitely appear from the detailed description to follow.

I accomplish the objects of my invention 25 by the devices and means described in the following specification. The invention is clearly defined and pointed out in the claim.

A structure which is a preferred embodiment of my invention is clearly illustrated 30 in the accompanying drawing, forming a part of this specification, in which:

Figure I is an end elevation of my improved binder device adjusted to one position.

35 Fig. II is an end elevation of my improved binder device adjusted to another position.

Fig. III is a side elevation of my improved binder device adjusted to the position shown in Fig. I.

Fig. IV is an end elevation adjusted to still another position.

Fig. V is a horizontal section on a line corresponding to line 5—5 of Fig. I, the 45 binder and sheets being removed from the holder.

Fig. VI is a detail section through the base and one of the bed members on a line corresponding to line 6—6 of Fig. V, showing the arrangement of the supporting rollers.

Fig. VII is an inside plan view of one of the binder members with sheets arranged thereon in offset relation, the binding members 55 of the binder being shown in section.

In the drawing similar reference characters refer to similar parts throughout the several views, and the sectional views are taken looking in the direction of the little arrows at the ends of the section lines. 60

Referring to the drawing, the base 1 is of such dimensions as to properly support the parts and is preferably a circular plate of wood. The binder comprises a pair of binder members 2 having binding members 65 3 extending between the same with which the notches 4 of the sheets 5 may be engaged. The binder illustrated is that shown in my Patent No. 1,174,458, dated March 7, 1916, and therefore further or detailed description as to its structure is unnecessary.

I provide a holder comprising a pair of spaced bed members 6 having inwardly inclined ends 7 constituting rests for the side members 8 of the holder when they are 75 collapsed. The bottom member 9 is mounted on the bed member 6 between the rests. The side members 8 are hinged to the bottom member at 10 so that they may be collapsible upon the rests as shown in Fig. II or swung 80 to an erected position as shown in Figs. I and III.

The side members are independently adjustable so that one may be adjusted to rest upon its rests 7, while the other is supported 85 in erected position as shown in Fig. IV. The side members are supported in their erected position by the collapsible braces or struts 11 formed of links pivoted to each other at 12, to the side members at 13, and 90 to the bed members at 14. On the under side of the bottom I mount a pivot block 15 for the vertical pivot 16, thus providing a swivel support for the holder.

To sustain the considerable weight which 95 the holder is frequently called upon to carry and permit its easy adjustment I provide the carrying rollers 17 which are journaled in the under sides of the bed members 6 radially of the pivot so that they travel upon 100 the base 1. With this arrangement of parts the holder may be swung on its swivel or pivot to bring either side of the sheets to the view of the operator, which is of great advantage, particularly in machine accounting. The sheets, where formed, as shown in Fig. VII, with a plurality of notches, may be arranged in an aligned body or offset relation, thus indicating to the operator selected 105 sheets for any desired purpose. 110

My improved binder device greatly facilitates the use of accounting sheets and loose leaf binders, particularly where it is desired to provide the same with records on both 5 sides.

Having thus described my invention, what I claim as new and desire to secure by Letters Patent, is:

In a device of the class described, the combination with a base, of a holder comprising 10 a pair of spaced bed members having inwardly inclined ends constituting rests, a bottom member mounted on said bed members between said rests, side members hinged 15 to said bottom member to collapse upon said

rests, collapsible braces for supporting said side members in erected position, a pivot block disposed centrally on the under side of said bottom member between said bed members, a pivot on said base, and rollers 20 traveling on said base disposed on said bed members radially of said pivot.

In witness whereof, I have hereunto set my hand and seal in the presence of two witnesses.

GEORGE P. WIGGINTON. [L.S.]
